UNITED STATES PATENT OFFICE.

ROBERT HOPE-JONES, OF NORTH TONAWANDA, NEW YORK; CECIL HOPE-JONES TEMPORARY ADMINISTRATOR OF THE PERSONAL ESTATE OF SAID ROBERT HOPE-JONES, DECEASED.

RELEASING DEVICE FOR ORGAN STOP-KEYS.

1,121,586.

Specification of Letters Patent. Patented Dec. 15, 1914.

Application filed December 27, 1910. Serial No. 599,432.

To all whom it may concern:

Be it known that I, ROBERT HOPE-JONES, of North Tonawanda, in the county of Niagara and State of New York, have invented certain new and useful Improvements in Releasing Devices for Organ Stop-Keys; and I do hereby declare the following to be a full, clear, and exact description of the same, reference being had to the accompanying drawings, forming a part of this specification, and to the reference-numerals marked thereon.

My present invention relates to musical instruments and more particularly to organs or instruments having the same general scheme of construction, and it has for its object to provide a simple and efficient means for releasing the stop keys from the influence of other operating means in order that they may be operated manually, when desired, independently of such.

A further object of the invention is to accomplish this result in an improved manner through the medium of a simple arrangement of electrical devices.

To these and other ends the invention consists in certain improvements and combinations of parts, all as will be hereinafter more fully described, the novel features being pointed out in the claims at the end of the specification.

In the drawings: Figure 1 is a side elevation of a stop key mechanism constructed in accordance with and illustrating one embodiment of my invention, the parts being shown in the positions they occupy before the stop is drawn. Fig. 2 is a similar view showing the positions of the parts after the stop is drawn; Fig. 3 is a fragmentary view of the same parts showing the initial position assumed by the finger portion of the stop key when operated. Fig. 4 is a fragmentary view of a modified form; Fig. 5 is a top plan view of the key shown in Figs. 1 to 3, and Fig. 6 is a detail view of the contacts established through the operation of the key.

Similar reference numerals throughout the several figures indicate the same parts. I contemplate the use of my invention in connection with the stops for the pedal keys of an organ. In organs of one type, arrangements are made whereby in drawing the stops preparatory to performing on one

manual, other stops for the bass or pedal keys are thereby automatically drawn to provide a suitable bass for that particular manual with regard to the stops that are drawn upon it. With the ordinary construction of pedal stop keys it has hitherto been necessary to provide an additional key known as a "release tablet" for releasing the pedal stop keys from the influence of the aforementioned automatic operating means which held them in either the in or out position before they could be manually controlled by their individual manipulation in case it was desired to alter them. This required two distinct movements of the hand of the performer, one to the release tablet and the other to the stop keys themselves. In the practice of the present invention I provide for accomplishing the release of the stop keys by manipulation of merely the keys themselves and by imparting thereto a movement, a continuation of which, operates the key to the desired position.

Referring more particularly to Fig. 1 of the drawings, 1 indicates a stop key pivoted on a rod or member 2 by means of an open bearing 3 on its under side that is held in engagement with the pivoted member by a spring 4 on a suitable supporting portion 5 of the organ structure, which spring also tends to maintain a key in either of what will later be described as being its in and out positions by passing across the center of pivotal movement. A rearwardly extending preferably metallic arm on, or extension of, the key, 6, moves in continuous contact with a contact member 7 mounted, in the present instance, on a lower rail 8 of the organ structure, but moves into contact with the companion contact member 9 only when the arm is elevated, as in Fig. 1, to the region of the offset portion 10 of such contact, as shown in Fig. 6, the position of the arm being in dotted lines. When in the raised position, therefore, the arm establishes a circuit through the contacts, which circuit, when closed, operates the stop mechanism that the key controls. In such case the forward or operating portion of the key is depressed, as in Fig. 2, and the stop may be said to be "out" or "drawn."

The complete mechanism whereby the bass stops are affected by the drawing of the stops on the manuals is too complicated,

as used, to warrant its disclosure herein. It is deemed sufficient to say that the manual stops close a circuit through wires 11 and 12 that control the air supply in each stop mechanism unit to a pair of oppositely disposed bellows 13 and 14. One of these bellows, the bellows 13 for instance, has a larger pressure area than its mate so that while both are connected to the arm 6 at 15 and 16, the former thereby acting to draw the stop and the latter to return it, when both are inflated the larger overcomes the smaller and negatives its effect, but when the larger is deflated the smaller acts to return the stop to normal position. The object in providing the smaller one is to make possible the automatic resetting of such stops as are necessary when the performer changes his manual stops. For instance, in drawing the corresponding suitable bass stops he wishes to throw out the suitable bass for the preceding manual stops, which bass is no longer applicable. However, it is only important to the present disclosure to say that both bellows are deflated by breaking the circuit through the wires 11, 12 as at 20—21 hereinafter described which wires are common to both of their circuits though these circuits may be separately affected at other points to bring about the resetting of the suitable bass combination as above referred to by the manual stop keys.

A solenoid 17, suitably energized, as by a battery 18 controls the switch 19 that opens and closes the circuit through the wires 11, 12 at contacts 20 and 21, such solenoid circuit comprising wires 22 and 23. One of these wires is connected to the arm 6 of the stop key, in the present instance through the medium of the contact 7, while the other leads to an arm 24 on an operating or finger portion 25 of the key 1 projecting outwardly beyond the rail 5 and 8 to be accessible to the fingers of the performer at the key board. This finger portion 25 moves with the key when the latter is operated in any manner but it also has a limited movement relatively thereto and to this end the two parts are connected by a resilient tongue or member 26, shown in dotted lines in the figures, but which is sufficiently stiff to maintain the parts in the normal relationship shown in Figs. 1 and 2 and to hold the electrical contact arm 24 on the finger portion in spaced-relationship to and between two oppositely disposed contacts 27 and 28 both electrically connected to and preferably mounted upon the arm 6 of the key. The range of movement of the finger-piece, however, relatively to its key permits the contact arm 24 thereon to move into engagement with either of the contacts 27 or 28 when the key is manually operated by means of the finger piece to either the in or out position, which engagement, in the present

instance, effects a relative disposition of the finger portion and its key adapting them for further joint movement. Such contact closes the circuit of the solenoid 17, operates the switch 19 and breaks the circuit through the wires 11 and 12 thereby throwing out the automatic devices then in control of the key by causing the deflation of both of the bellows 13 and 14, or either of them. When both bellows are deflated there is no opposition to the movement of the arm 6 and hence the key is free to move in either direction with a continued pressure on the finger portion.

In Fig. 4 is illustrated a construction of the finger piece contact arm 24 that I prefer in which embodiment the end of the arm is looped or doubled providing two contacts 27^a and 28^a on this arm instead of on the arm 6, which contacts are disposed upon opposite sides of the pivot member 3 for the key and the wire 23^a is connected to this member. The other wire 22^a of the circuit, comprising the battery 18^a and the solenoid 17^a, is connected up directly to the arm 24 as before. Of course, the arm 24 on the finger portion must be insulated from the rest of the key 1, but the two parts are ordinarily made of insulating material themselves and hence the resilient connecting part 26 may be made of metal.

I claim as my invention:

1. In a stop mechanism for musical instruments, the combination with a stop key movable to in and out positions and having a finger portion and means for mechanically moving the key independently of said finger portion to one of said positions and for holding it in such position, of a releasing device for rendering said means inoperative, and controlling connections between the releasing device and said finger portion. 100
2. In a stop mechanism for musical instruments, the combination with a stop key movable to in and out positions having a relatively movable finger portion also movable therewith and means for mechanically moving the stop key otherwise than by manipulation of the finger portion to one of said positions and for holding it in that position, of a releasing device for rendering said means inoperative, and controlling connections between the releasing device and the finger portion. 105
3. In a stop mechanism for musical instruments, the combination with a stop key movable to in and out positions having a relatively movable finger portion by means of which it may be manually moved to the same positions, said finger portion being normally movable therewith between such positions, of means for mechanically moving the stop key otherwise than by manipulation of the finger portion and for holding it in one of its positions, a releasing device 120

for rendering said holding means in operative and controlling connections between the releasing device and the finger portion operative when the latter is reversed in manually returning the stop.

4. In a stop mechanism for musical instruments, the combination with a stop key having a relatively movable finger portion movable therewith to in and out positions and means for mechanically operating the stop otherwise than by manipulation of the finger portion and for holding it in one of said positions, of an electrically operated releasing device for rendering said holding means inoperative, contacts in the circuit of such device and means connected with the finger piece and coöperating with the contacts to operate the releasing means as the finger piece is reversed to manually return the stop.

5. In a stop mechanism for musical instruments, the combination with a stop key movable to in and out positions and having a relatively movable finger portion for the manual operation thereof, of means for mechanically operating the key to one of said positions otherwise than by manipulation of the finger portion and holding it in such position, an electric circuit controlling said means and contacts in such circuit under the control of the finger portion of the key.

6. In a stop mechanism for musical instruments, the combination with a stop key movable to in and out positions, and having a relatively movable finger portion for the manual operation thereof, of means for mechanically moving the key to one of said positions otherwise than by manipulation of the finger portion and holding it in such position, an electrical circuit controlling said means and a pair of contacts in said circuit one of which is carried by the finger portion and moved relatively to the other by the movement of the finger portion relatively to its key.

7. In a stop mechanism for musical instruments, the combination with a pivoted stop key movable to in and out positions

and having a relatively movable finger portion for the manual operation thereof, of means for mechanically moving the key to one of said positions otherwise than by manipulation of the finger portion and holding it in such position, an electrical circuit controlling said means and a pair of contacts in said circuit one of which is formed by the pivot of the key and the other of which is carried by the finger portion and moved relatively to the first by the movement of said finger portion relatively to its key.

8. In a stop mechanism for musical instruments, the combination with a pivoted stop key movable to in and out positions and having a relatively movable finger portion for the manual operation thereof, of means for mechanically moving the key to either of said positions otherwise than by manipulation of the finger portion and holding it there, an electrical circuit controlling said means and a pair of contacts in said circuit, one of which is formed by the pivot of the key and the other of which comprises a double contact member formed by an arm carried by the finger portion and doubled about the first to contact therewith when the finger portion is moved in either of two directions to manually set the stop key in either position.

9. In a stop mechanism for musical instruments, the combination with a stop key movable to in-and-out positions and means for mechanically operating it to one of said positions and for holding it there, of a finger portion for said key, a resilient member connecting it for movement therewith and also permitting its movement relatively thereto, and connections between the key operating and holding means and the finger portion for throwing the former out of control of the key as the finger portion is moved relatively to the key.

ROBERT HOPE-JONES.
